(57) **CLAIM**

I claim the ornamental design for pump components, as shown and described.

DESCRIPTION

FIG. 1 is a first perspective view of pump components in accordance with an embodiment of my new design illustrating a pump cap;

FIG. 2 is a second perspective view of the pump components of FIG. 1;

FIG. 3 is a rear elevation view of the pump components of FIGS. 1-2;

FIG. 4 is a front elevation view of the pump components of FIGS. 1-3;

FIG. 5 is a right side elevation view of the pump components of FIGS. 1-4;

FIG. 6 is a left side elevation view of the pump components of FIGS. 1-5;

FIG. 7 is a top plan view of the pump components of FIGS. 1-6; and,

FIG. 8 is a bottom plan view of the pump components of FIGS. 1-7.

The portions of the pump components shown in broken lines in the figures depict unclaimed environmental subject matter, are for illustrative purposes only, and form no part of the claimed design.
